UNITED STATES PATENT OFFICE.

JOHN D. WILBER AND A. BEVERLY SMITH, OF TOWANDA, PENNSYLVANIA.

STAPLING-MACHINE.

SPECIFICATION forming part of Letters Patent No. 330,950, dated November 24, 1885.

Application filed April 17, 1882. Serial No. 58,487. (No model.)

To all whom it may concern:

Be it known that we, JOHN D. WILBER and A. BEVERLY SMITH, citizens of the United States, residing at Towanda, county of Bradford, State of Pennsylvania, have invented a new and useful Improvement in Stapling-Machines, of which the following is a specification.

In the accompanying drawings, Figure 1 is a top view of the machine. Fig. 2 is a side elevation, partly sectional, through the line x x , Fig. 1. Fig. 3 is a front elevation of the machine with portions broken away to show staple forming, cutting, and driving mechanism. Fig. 4 is a detailed view of clutching mechanism. Fig. 5 shows details of the clinching mechanism. Fig. 6 shows manner of driving and clinching staples. Fig. 7 is a sectional view of staple former and driver, showing grooves in former in which staple rests after being formed and in which ribs on staple-driver slide. Fig. 8 is a section of staple-driver with cross-head. Fig. 9 shows adjustable plane table. Fig. 10 shows adjustable angular table.

Similar letters refer to similar parts throughout the several views.

On shaft A' is rigidly secured wheel A, of sufficient diameter and thickness to carry the proper cams in; also, wheel H, carrying mutilated gear h, for operating wire-feeding mechanism, and stud h⁸, for operating clinching device; also, wheel I, containing spring i and bolt i⁶; also, on shaft A' loosely runs the band-wheel J, which, when engaged by clutch-pins i⁴ i⁴ with clutch-bolt i⁶ in wheel I, gives motion to the entire machine.

In face of wheel A, Fig. 3, is cam-groove a², in which works stud c⁶, Fig. 2, attached to staple-former C. In periphery of wheel A is cam-groove a, Figs. 1 and 2, in which works stud C⁴ on staple-mandrel C³. The mutilated gear h on wheel H engages with pinion h', secured to gear-wheel h², both running on a journal adjustably secured by dovetailed piece h⁵ to standard h³. Gear-wheel h² engages with gear-wheel h⁴, secured to shaft g⁴, revolving in journals g³ g³, Fig. 1. On the other end of shaft g⁴ is the milled wheel G, rigidly secured. Underneath milled wheel G is idler g, also milled, and running in journals g' at proper distance from G. If desired, the journals of

idler g can rest upon a rubber or other suitable spring to allow for variation in the size of wire used. Block e³, sliding in ways F, 55 Figs. 1 and 3, has secured to its end knife e¹, also ways e e, in which slides block E, having secured to it knife e⁵, and carrying forked arm e¹. On block e³ is wire-guide e², also pointer f¹, sliding over scale f on ways F. The block e³ can be secured in any desired position by set-screw f² in ways F. The curved lever e⁴, hinged to journal g³ by pin e⁵, extends through the forked arm e¹ sufficient distance to engage with pin a⁴ on wheel A. Lever e⁴ is sustained 65 in position by spring e⁸ resting on way F. Staple-former C slides freely in ways C' C'. On the inner faces of its forks or prongs, and extending its entire length, are grooves d' d', Fig. 7, in which staple is pressed when formed, 70 and in which ribs d d, Figs. 3 and 7, of staple-driver D work. Former C and standard C² form guides, through which the staple-driver D works. On staple-driver D is shoulder c², on which rests spiral spring c'. Cross-head B, 75 75 of proper shape, containing in its upper portion the angular recess b, is attached to driver D, Figs. 3 and 8. In B works pin a³, extending from projection A' on wheel A. On plate A² is staple-mandrel C³, sliding in dovetailed 80 ways formed in lower portion of standard a'. On C³ is stud c⁴, which works in cam-groove a on periphery of wheel A. Below plate A², directly under staple forming and driving mechanism, is table-standard L, supported by 85 spring k⁴ k⁴ k⁴, Fig. 2, which rests on base K. In standard L, Fig. 3, is slot k⁶, working over stop k⁵, which limits the upward movement of standard L by spring k⁴. The base K is made so as to form a support for the spring k⁴ 90 and guides or ways for standard L. Attached to standard L is the clinching mechanism, (shown in its various detail in Fig. 5,) in which l' is a circular groove in which clinchers l' l' vibrate around pin l⁶, forming common center. 95 The lower portions of l' l' contain slots l' l', through which projects a pin on the end of lever l². The clinchers l' l' are so formed as to cross each other. Lever l² is fulcrumed at l³ and extends downward, having in its lower part opening l⁵, in which one end of lever k² works. k² is fulcrumed on pin k³, Fig. 2, and engages with lower end of lever h⁶, which is fulcrumed on stud k'. The upper end of h⁶

engages with pin h^8 on wheel H. The plane table, Fig. 9, designed for flat work, is attached to standard L and secured by set-screw o. The shouldered projection o² on standard 5 L, Fig. 2, enters recess o', Fig. 9, the throat-plate l forming part of the table. The angular table, Fig. 10, fits on and is secured to standard L in a similar manner to the plane table, Fig. 9, and is intended for use in work 10 requiring staples to be driven through the center of a fold, as through the center of a pamphlet, the angular-shaped table being preferable for that purpose. In Fig. 4 lever i² is fulcrumed on pin i³, and carries on its upper end the plunger i⁵. On lower end of i² is catch i⁷, hinged at i³ with i², and is held in position by spring i⁹. M is a rod sliding in standards m² m², and connected at one end with a treadle or other suitable mechanism, and 15 having secured to its other end plate m by set-screw m'. The coiled spring m³ encircles M between supports m² m², holding M in proper position.

In operation motion is given the band-wheel J, which carries on its face pins i⁴ i⁴. 20 The rod M, Fig. 4, being drawn forward, the plate m engages with catch i⁷, and through lever i² thrusts plunger i⁵ against clutch-bolt i⁶, forcing it through wheel I and clutching 25 against pin i⁴. Plate i¹, secured to standard a' by bolt i⁹, contains a slot, through which plunger i⁵ works, and into which at each revolution, bolt i⁶ is thrust by spring i¹, thereby unclutching wheel I from band-wheel J. As 30 the rod M is drawn forward after making the clutch, the point of the catch i⁷ slips over the edge of plate m, thereby releasing the lever i² and allowing the plunger i⁵ to be forced back by the bolt i⁶ on its arriving opposite the 35 slot in plate i¹. The rod M being released, spring m³ forces it back to its original position, the hinge of catch i⁷ allowing plate m to pass readily underneath the point of i¹. Should 40 continuous motion be desired, plate m is re-45 volved until its longer face will engage with clutch i⁷ and not pass under, thereby retaining the lever i² in position to keep the machine in clutch. On motion being given, the mutilated gear h engages with pinion h', which is secured 50 to wheel h², which in turn engages wheel h⁴, giving sufficient rotation to milled wheel G to feed the proper length of wire. For different-sized staples, requiring different lengths of 55 wire, the necessary variation in movement of milled wheel G is obtained by changing the sizes of intermediate gear-wheel, h². Gear-wheels of the required sizes, having pinions h' of a standard size, are attached to dovetailed 60 blocks, h⁵ fitting in standard h³. The wire g², being fed by rotation of milled wheel G, passes through guide e², between knives e⁶ and e⁷, Fig. 3, passing the proper distance beyond and over the mandrel C³. At this point the stud a³ on wheel A enters the angular recess b 65 in cross-head B, allowing spring e' to force driver D down firmly upon wire g², clamping it upon mandrel C³, a small groove in bottom of driver

D centering the wire and holding it rigidly while being cut and formed. The angular recess b in cross-head B allows the said dropping of D, independent of action of stud a³, during a portion of its revolution. At this moment the pin a⁴ strikes lever e⁴, forcing down knife e⁶ past knife e⁷, and thus severing the wire by a shear cut. At this instant cam-groove a², operating on former C, forces it down and over mandrel C³, forming the staple, and clamping the material to be stapled between it and the table. At this point cam a in periphery of wheel A retracts the mandrel C³ a proper distance. At this time stud a³ 70 engages cross-head B, forcing driver D down, driving the staple into and through the article to be stapled. The ends of the staple striking the semicircular anvil l⁴, Fig. 6, 75 are forced outwardly over the inclined faces of clinchers l' l'. At this moment, and while the article to be stapled is held firmly between the ends of former and driver and the spring-table, stud h⁸ on wheel H strikes lever h⁶, and 80 through levers k² and l² a quick upward thrust is given to clinchers l' l', bending the prongs of the staple outward at right angles and firmly against the article stapled. The stud h⁸ having disengaged from lever h⁶, the clinching mechanism is brought to its first position 85 through the action of a suitable spring or counter-weight on lever h⁶. The former C and driver D are then raised by cam a² and stud a³, and C³ is thrust forward by cam a, all in 90 readiness for another staple. The object of supporting the tables by spring-standard L and spring k⁴ is to make an automatic adjustment for the varying thickness of work. The proper distance for inserting the work between plate A² and the table is maintained by stop k⁵ on base K. Staple-former C and driver D are brought down sufficiently to compress spring k⁴ in stapling the thinnest work. The spring is of sufficient strength to 95 properly clamp the thinnest work to be stapled, and, as thicker material requires heavier clamping, this object is attained by the proportionate greater or less compression of the spring k⁴ by the varying thickness of the work 100 inserted. The advantages of supporting the table on a spring or springs are, obviating the adjustment of the machine to each thickness of work and the liability to breakage through 105 imperfect adjustment or accidental insertion of any extra thickness of material, which objections attach to every machine having a 110 positive adjustment to its table.

The irregular V-shaped opening l⁵ in l², in which lever l² works, is for the purpose of 115 giving the same thrust to the clinchers l' in whatever position the table may be, through having thicker or thinner material on it for stapling. This is accomplished by widening the opening C⁶ in proportion to the lessening 120 of the working radius of lever l².

Having thus described our invention, what we claim as new therein, and desire to secure by Letters Patent, is—

1. The mutilated gear h , changeable wheels $h' h^2$, and gear-wheel h^4 , in combination with the milled feed-wheels G and g , substantially as and for the purpose specified and shown.
- 5 2. In a wire-stapling machine, the pin a^4 , spring e^8 , lever e^4 , arm e' , block E , and knife e^6 , in combination with ways $e e$, slide e^9 , and knife e^7 , all arranged substantially as shown and specified.
- 10 3. In a wire-stapling machine, the recessed cross-head B , in combination with driver D , spring c' , and mandrel C^3 , substantially as and for the purpose set forth.
- 15 4. The staple-driver D , with its cross-head B , guide C^2 , spring c' , shoulder c^2 , and crank-pin a^3 , in combination with mandrel C^3 and staple-former C , substantially as and for the purpose set forth.
- 20 5. In a wire-stapling machine, the table-standard L , with angular shoulders $o^2 o^3$, and throat-plate l , so arranged as to form an attachment to suitable tables, substantially as set forth and shown.
- 25 6. In a wire-stapling machine, the table-standard L , throat-plate l , shoulders $o^2 o^3$, in combination with table P , having opening p' , and secured by set-screw p , and shoulder o^3 , substantially as and for the purpose set forth and shown.
- 30 7. The anvil l^4 , with circular sides forming ways, in combination with the clinchers $l' l'$, arranged substantially as shown and specified.
8. In a wire-stapling machine, the clinchers $l' l'$, with slots $l^3 l^3$, working on a common center, l^6 , in combination with anvil l^4 and lever l^7 , substantially as and for the purpose set forth. 35
9. The lever l^7 , containing V-shaped slot l^5 , in combination with clinchers $l' l'$, anvil l^4 , throat-plate l , and lever k^2 , substantially as and for the purpose shown and described. 40
10. In a wire-stapling machine, the pin h^8 , levers $h^6 h^2$, in combination with lever l^2 and clinchers $l' l'$, substantially as and for the purpose specified. 45
11. The combination of lever k^2 and lever l^2 , for operating the clinchers, and having opening l^5 , with standard L , having recess k^7 , substantially as described. 50
12. In a wire-stapling machine, the combination of staple-former C , mandrel C^3 , staple-driver D , pins $c^5 c^4 a^3$, cross-head B , and cam, having grooves $a a^2$, all arranged substantially as and for the purpose shown and specified.
